UNITED STATES PATENT OFFICE.

BUTLER BAKER, OF HAYMARKET, VIRGINIA.

SHAFT AND CROSSBAR CONNECTION.

Application filed August 10, 1925. Serial No. 49,301.

The invention relates to shaft and cross bar connections for conventional forms of wagon shafts, and has for its object to provide a bracket whereby the cross bar end may be easily and quickly rigidly secured to a shaft after the tenon of the cross bar has been broken therefrom which is a common difficulty with shafts as at present constructed.

10 A further object is to provide a U-shaped bracket arching the outer and upper sides of a shaft and having its arms connected to the cross bar of the shafts, and provided with an inwardly extending lug between its 15 arms which is disposed in the tenon aperture of the shaft, thereby rigidly connecting the cross bar to the shaft.

With the above and other objects in view the invention resides in the combination and 20 arrangement of parts as hereinafter set forth, shown in the drawing, described and claimed, it being understood that changes 25 in the precise embodiment of the invention may be made within the scope of what is claimed without departing from the spirit of the invention.

In the drawing:—

Figure 1 is a top plan view of a conventional form of wagon shaft showing the 30 bracket applied thereto.

Figure 2 is a transverse sectional view taken on line 2—2 of Figure 1.

Figure 3 is a view in elevation of the inner end of the bracket.

35 Referring to the drawing, the numeral 1 designates spaced shafts of a conventional form of wagon, and 2 a transversely disposed cross bar adjacent their rear ends, which crossbar is provided with tenons 3, which are received in transversely disposed apertures 4 in the shafts 1. It has been found that the tenons 3 easily break and it is extremely difficult to properly repair the shafts 40 without putting in an entirely new cross bar, and to obviate this difficulty a U-shaped bracket 5 is provided. The U-shaped bracket 45 arches the outer, upper and lower sides of the shaft 1, and has its arms 6 overlying the upper and lower sides of the adjacent 50 end of the cross bar 2, and which arms are secured to the cross bar by means of the bolts

7, which pass downwardly through the arms and the cross bar. It will be noted that the U-shaped bracket will hold the shaft in close engagement with the outer end of the cross bar, from which the tenon has been removed after breaking thereof, however it will also be noted that to maintain the cross bar against movement towards the forward and rear ends of the shaft it will be necessary 55 to provide interengaging means between the bracket 5 and the shaft. To accomplish this result bracket 5 between its arms 6 is provided with an inwardly extending integral lug 8, which lug, when the bracket is 60 forced to position on the cross bar 2 is received in the aperture 4 of the shaft 1, therefore it will be seen that the crossbar and the shaft will be rigidly held in relation to each 65 other, against movement and at substantially right angular positions. 70

From the above it will be seen that a repair bracket is provided for the connection between a cross bar and a wagon shaft, which bracket is formed from a single piece 75 of metal, simple in construction, and which when placed in position positively holds and braces the crossbar and shaft in relation to each other.

It will also be seen that incident to the 80 simple construction of the bracket from a single piece of metal, the brackets may be cheaply manufactured and sold.

The invention having been set forth what is claimed as new and useful is:—

85 The combination with a shaft having an aperture extending transversely therethrough, a cross bar having its end in abutting engagement with the shaft in registration with the aperture therein, of a U-shaped bracket arching the outer side of the shaft, arms of said U-shaped bracket engaging the upper and lower sides of the shaft and cross bar, securing means for securing said arms to the cross bar and an integral inwardly 90 extending lug carried by the U-shaped member between the arms thereof and extending into the aperture in the shaft. 95

In testimony whereof I have signed my name to this specification.

BUTLER BAKER.
